UNITED STATES PATENT OFFICE.

CLYDE L. CARTRE, OF AURORA, ILLINOIS.

MILK-BOTTLE HOLDER.

1,295,120.

Specification of Letters Patent. Patented Feb. 25, 1919.

Application filed August 13, 1917. Serial No. 186,033.

To all whom it may concern:

Be it known that I, CLYDE L. CARTRE, a citizen of the United State, and resident of Aurora, in the county of Kane and State of Illinois, have invented certain new and useful Improvements in Milk-Bottle Holders, of which the following is a specification.

This invention relates to new and useful improvements in holders and more particularly to a holding device which is adapted to receive a milk bottle therein, to securely lock the same, and prevent its theft after its delivery, until time it is removed by the owner.

15 A further object of the invention is to provide a milk bottle holding device of this character adapted to be secured to the outer side of a door or the like, and provided with means whereby the bottle may be securely locked in position, and can only be released by a locking pin that is operable from the inner side of the door. The device is normally in open position, but when a bottle has been placed therein, and the slidable 20 locking cap positioned down over the top of the same, it will be impossible to release the bottle until the top releasing means operable from the inner side of the door have been withdrawn, so as to allow the locking cap 25 to be raised.

Another object of the invention is to provide a device of this character which is easily and simply constructed, inexpensive to manufacture, and one which will be very 30 efficient in operation.

With these and numerous other objects in view, my invention consists of the novel features of construction, combination and arrangement of parts which will be herein 35 referred to and more particularly pointed out in the specification and claims.

In the accompanying drawings:—

Figure 1 is a detail perspective view of the device applied to a door or the like, and 40 Fig. 2 is a vertical section through the same.

In describing my invention I shall refer to the drawings in which similar reference characters designate corresponding parts 45 throughout the several views.

The numeral 1 designates a door or the like, to which is secured a vertically disposed support 2, which forms a casing, and said support having a laterally projecting

lip 3 on the lower edge thereof. Secured on 55 the upper surface of the lip 3 is a socket member 4, adapted to receive a projecting shank 5 on the lower surface of a bottle receiving base 6. The base 6 is provided with an upwardly projecting annular flange, and is of such size as to receive the conventional type of milk bottle therein. The projecting shank 5, and the socket member 4 are externally and internally threaded correspondingly, so that the base 6 which is ordinarily 60 stationary is adapted to be removed.

The supporting casing 2 is provided with a vertical longitudinally extending passage 7 therein, that extends from adjacent the top 70 downwardly along the same, and said passage is provided with a pair of communicating upper and lower openings 8 and 9 respectively, for a purpose to be hereinafter more fully described. A recess 10 is provided adjacent the upper end of the passage 75 7 adapted to receive a coil spring 11 therein that coöperates with the locking means of the device in the manner to be hereinafter more fully described.

The locking means employed in this type 80 of bottle holder includes a locking cap 12 that is disposed in alignment with the base 6, and which is provided with a projecting portion 13 that extends through the opening 8, and which has a downwardly extending 85 arm 14 slidably positioned within the passage 7 in the support 2. The inner side of the arm 14 has a rack 15 formed thereon, and secured to the opposite side or outer side of said arm adjacent the bottom thereof is 90 a bottle holding clip 16 formed of a pair of hingedly connected arms, that are adapted to engage the bottle when positioned between the base and locking cap, intermediate the top and bottom thereof, to securely clasp 95 the same in position. The arms of the clip 16 are hingedly connected to the arm, and hence it is obvious that upon sliding movement of the said arm the clip will be engaged accordingly. The opening 9 through 100 which the arm is projected is elongated, so as to allow said movement. A spring pressed pin 17 having a knob 18 on the outer end thereof projects through the door 1, and inner side of the support 2, the operating 105 spring 19 thereof comprising a coil spring surrounding said pin, and positioned in an enlarged recess 20 adjacent the inner side

of the support 2. The coil spring 19 will tend to force the pin 18 to the passage 7, and hence into engagement with the rack 15 on the arm 14.

5 In operation when the various parts of the device are disposed as shown in Fig. 2 of the drawings, and a milk bottle is placed on the base 6, the body portion of said bottle will be engaged by the spring arms of the 10 clip 16, and the top of the bottle will be disposed directly beneath the movable locking cap 12. Upon moving the cap downwardly, the arm 14 will slide correspondingly along the passage 7, until the cap engages the top 15 of the bottle. Owing to the fact that the locking pin 15 is spring pressed, the inner end thereof will slide over the rack but will prevent the arm 14 from moving upwardly until the pin is withdrawn. This will 20 securely lock the cap 12 on the top of the bottle, and prevent the removal of the said bottle. The coil spring 11 facilitates the movement of the arm 14 in the passage 7, when the same is moved down to engagement with the top of the bottle.

25 The operation of this type of milk bottle holder will prevent the theft of the milk between the time it is delivered, and collected by the user. The device is adapted 30 to be applied to the outer side of a door or the like, and when the bottle is placed in position, the locking cap moves down over the top of the same, the cap will be automatically locked, and cannot be lifted until 35 the pin 17 is released by withdrawing the same, the handle of said pin being positioned on the inner side of the door, and hence being only accessible to the user.

40 From the above description, taken in connection with the accompanying drawings, it is thought that a clear and comprehensive understanding of the construction, operation and advantages of my invention may be had, and while I have shown and described 45 the device as embodying a specific structure,

I desire that it be understood that such changes may be made in said structure as do not depart from the spirit and scope of the invention as claimed.

Having fully described my invention, 50 what I claim as new, and desire to secure by Letters Patent, is:—

1. A milk bottle holder of the class described including a bottle receiving base, a locking member disposed above said base 55 and in alinement therewith, said member having a spaced depending slidably mounted arm, a bottle engaging clip carried thereby, a rack on said arm, and a spring pressed locking pin adapted to normally engage said 60 rack.

2. A milk bottle holder including a vertically disposed support having a projecting lip, a bottle holding base on said lip, a cap member disposed in alinement with said 65 base, said member having a spaced depending arm slidably mounted in said support, a rack on said arm, a bottle engaging clip carried by the arm, and a spring pressed locking pin extending through the rear side of 70 said support and engaging said rack.

3. A bottle holder including a body portion having a longitudinal way formed therein, a laterally extending arm on the lower end of the body portion provided with 75 a screw threaded socket, a cup carrying a screw threaded shank received in the socket, an angle arm having one part slidably in said way and formed with a serrated edge, a cap carried on the outer end of the angle arm 80 in vertical alinement with said cup, spring means engaged with a portion of the angle arm for placing the same under pressure, a spring clip secured to the angle arm extending laterally from the body portion, and a 85 catch slidably in the body portion engageable with the serrated edge of the angle arm.

In testimony whereof, I affix my signature hereto.

CLYDE L. CARTRE.
